UNITED STATES PATENT OFFICE.

HEINRICH KOPPERS, OF ESSEN-ON-THE-RUHR, GERMANY, ASSIGNOR TO H. KOPPERS COMPANY, OF CHICAGO, ILLINOIS, A CORPORATION

CUPOLA GAS-GENERATOR.

1,099,257.

Specification of Letters Patent.

Patented June 9, 1914.

Application filed October 28, 1913. Serial No. 727,735.

To all whom it may concern:

Be it known that I, HEINRICH KOPPERS, a citizen of the German Empire, residing at Essen-on-the-Ruhr, in Germany, have invented certain new and useful Improvements in Cupola Gas-Generators, of which the following is a specification.

The object of this invention is to provide improved means for leveling the fuel in a cupola gas generator in such a manner as to produce a fuel surface well adapted for emission of gas to the eduction pipe. To this end I use in the upper part of a generating chamber a rotatable gas eduction pipe having a downwardly directed flared intake end to which a leveling appliance, adapted for the purpose stated, is attached. Between the edge of the flared end of said pipe and the wall of the generator I leave just sufficient space for the fresh fuel to descend from above the flared part of the pipe, and I make the wall of the said flared part slope at an angle approximating to the normal slope of the fuel at the top of the charge. The pipe, with its flared part, is rotated so as to distribute the fresh fuel evenly around it, to which end I may place ribs on the flared part, and the descending fuel has a natural tendency to form a cavity under the pipe, the function of the leveling appliance being to shape and level the surface of this cavity. The circumference of the latter coincides with the circumference of the orifice at the flared intake end of the pipe. A regular and efficient gas-emission surface is thus insured, though the fuel is fed in laterally of the eduction pipe and of the vertical axis of the generator.

The invention is illustrated in the accompanying drawing, which is a vertical section of the generator.

In the drawing, 10 designates the generator chamber or fuel receptacle, which is closed at the bottom by an ash-pan 11, to which is fixed the stepped grate 12 for the emission of slag or clinker, the pan and grate being rotated by means of worm gear 13. The gas eduction or take-off pipe 14 is centrally arranged at the upper part of the generator, and is rotatable, the pipe being for this purpose mounted on a bearing with a liquid seal 18. Shafts 22, 23, and bevel gears 24, 25, connect the pipe 14 to the worm gear 13, so that the pipe is rotated at a speed bearing a suitable relation to the

speed or rotation of the grate. An annular chamber 19, open at the bottom to the main generator chamber, is formed around the pipe 14, and the discharge end 16 of the fuel hopper 17 is joined to the wall of this chamber 19. The pipe 14 is flared at its lower end, within the main chamber, to form a hollow truncated cone 20, having ribs 21 projecting from its sides. The slope of the sides of this cone approximates to the normal slope of the fuel at the top of the charge, and the circumference of the cone at the bottom is so spaced from the wall of the main chamber as to leave an annular gap just adequate for the fresh coal to pass through. Leveling members or bars 15 are fixed across the bottom of the cone, these members having a downward parabolic curvature.

The charge introduced at 16 from the hopper 17 partly fills the space in the main chamber above the cone 20, this space being utilized as a kind of storage chamber, in which the fuel is pre-heated. The rotating cone 20 evenly distributes the fuel in this space, the distributing action being assisted by the ribs 21. The distributed fuel descends uniformly through the gap around the lower edge of the cone 20, and after clearing the said edge of course has a tendency to slide inward, so that there is a natural tendency for the fuel to form a cavity below the induction pipe. The surface of this cavity is leveled and made regular by the leveling members 15. The cone 20 and the leveling members thus coact to produce under the eduction pipe a fuel surface well adapted for the emission of gas to the pipe. It is well known that the provision of such a surface is a highly important factor in the manufacture of gas.

I claim:

1. A cupola gas generator comprising a fuel receptacle, a rotatable gas take-off pipe having a conically flared lower intake portion that is accommodated within the upper part of said receptacle, and fuel-leveling means extending across the bottom of said intake portion and rotatable with the take-off pipe, said means being adapted to produce a leveled gasifying fuel surface below said intake portion of the take-off pipe.

2. A cupola gas generator comprising a fuel receptacle, a rotatable gas take-off pipe having a conically flared lower intake por-

tion that is accommodated within the upper part of said receptacle, and parabolic fuel-leveling means extending across the bottom of said intake portion and rotatable with the 5 take-off pipe, said means being adapted to produce a paraboloidal fuel-cavity underneath the intake portion of the take-off pipe.

In witness whereof I have signed this specification in the presence of two witnesses.

HEINRICH KOPPERS.
